UNITED STATES PATENT OFFICE.

EDMOND B. SLATER, OF MERIDEN, CONNECTICUT, ASSIGNOR TO THE FOSTER, MERRIAM & COMPANY, OF SAME PLACE.

FURNITURE-CASTER.

SPECIFICATION forming part of Letters Patent No. 610,309, dated September 6, 1898.

Application filed March 19, 1898. Serial No. 674,472. (No model.)

To all whom it may concern:

Be it known that I, EDMOND B. SLATER, a citizen of the United States, residing at Meriden, in the county of New Haven and State 5 of Connecticut, have invented a new and useful Improvement in Furniture-Casters, of which the following is a full, clear, and exact description, reference being had to the accompanying drawings, forming a part of this specification, in explaining its nature.

The invention relates especially to the horn of a furniture-caster; and it consists in providing a peculiar-shaped blank of flat metal and the horn made therefrom.

5 Referring to the drawings, Figure 1 is a view in plan of the blank. Fig. 2 is a view in perspective of the horn made from the blank. Fig. 3 is also a view in perspective of the said horn turned from the position represented in Fig. 2. Fig. 4 is a view in side elevation of the complete caster. Fig. 5 is a view, partly in elevation and partly in vertical section, of the complete caster.

The blank A from which the horn of the 5 caster is formed is punched or otherwise made from sheet metal, and it has integrally-connected sections a a' , which form the arms of the complete horn-sections a^2 a^3 , which are adapted to form the upper and lower pinte- 0 bearments, and the connecting-section a^4 , uniting the arm-forming sections and the two bearing-forming sections. The arm-forming sections preferably are curved from the end of the connecting-section a^4 and have at their 5 outer ends the holes a^5 . The arm-forming sections also have at their upper ends the shoulders a^6 . The pinte-bearing sections a^2 a^3 each have a pinte-hole a^7 , and each preferably has the curved back a^8 on each side of its juncture with the cross-bar a^4 , the shoul- 0 der a^9 , and the straight edge a^{10} , although the form of this edge is immaterial. The blank thus shaped or similarly shaped is formed at one operation of a punch and die, and it is 5 then submitted to a further forming opera- 0 tion whereby it is converted into the complete horn and whereby the connecting-section a^4 is curved or bent to form a side wall b of the complete horn B and the arm-forming sections a a' brought parallel with each other to form

the arms b' of the horn and to bring the holes a^5 in line with each other, the arms being separated from each other by a space sufficient to receive the caster-roll C and the holes a^5 acting to receive the cross-pin c, which secures 55 the caster to the horn-arms.

The pinte-bearing sections a^2 a^3 are bent to a right angle to the wall b and form the horizontal supports b^2 b^3 for the pinte D, which are separated from each other by the width 60 of the wall. They are turned in the same direction, so that the pinte-holes a^7 are brought into line with each other, and their curved edges rest upon or bear against the top and bottom edges of the said wall b , while 65 their shoulders a^6 a^9 interlock with the shoulders a^4 at the upper ends of the arms and the intermediate section between the arms and form spacing or distance pieces which prevent the further closing of the arms to- 70 ward each other.

The pinte is attached to the supports b^2 b^3 in any of the usual ways. I have represented a conventional one in which the pinte is represented as having a head d at its lower end, 75 beneath the lower support b^3 , and a washer d', which is pressed or otherwise united to the pinte and is carried by it immediately above the upper support b^2 .

The advantages of the invention arise from 80 the simplicity of the construction, its strength, and the cheapness with which it can be made, as but two operations are necessary for forming the complete horn.

I do not wish to be understood as confining 85 myself to the especial form of blank shown or to the particular shape of horn obtained from it, as there may be various changes in these forms and shapes which will not modify the principle of the invention.

Having thus fully described my invention, I claim and desire to secure by Letters Patent of the United States—

1. In a blank for forming horns, the arm-forming sections a , a' , having the holes a^5 and 95 shoulders a^6 , the pinte-forming supports a^2 , a^3 having the shoulders a^9 and the holes a^7 and the integral connection a^4 .

2. As an improved article of manufacture the caster herein described, the same compris- 100

ing a horn B formed from a one-piece flat metal blank having a vertical rear wall b, forward-extending parallel roll-supporting arms b', flat pintle-supporting plates b², b³ extending 5 forward from the upper and lower edges of said back wall b, the upper of which has both sides extended upon said arms b' and is supported thereby as well as by the back, the pintle D carried by said supporting-plates 10 b², b³, and the caster-roll attached by a pin to said arms.

3. In a caster-horn a vertical wall, roll-supporting horns extending from and integral with said wall, and having shoulders a⁶, pintle-supports integral with said wall and parallel with each other, arranged to bear upon or against the edges of said wall, and provided with shoulders a⁹ which coöperate with the 15 shoulders a⁶ of the horn and also having the pintle-holes a⁷ and the pintle supported or carried by said pintle-supports.

EDMOND B. SLATER.

In presence of—

JAMES R. SUTLIFF,
J. L. RUTHERFORD.
